United States Patent Office.

DEXTER H. CHAMBERLAIN, OF WEST ROXBURY, MASSACHUSETTS.

Letters Patent No. 63,611, dated April 9, 1867.

IMPROVED METHOD OF CASTING TYPE ON PRINTING-WHEELS.

The Schedule referred to in these Letters Patent and making part of the same.

TO ALL WHOM IT MAY CONCERN:

Be it known that I, DEXTER H. CHAMBERLAIN, of West Roxbury, in the county of Norfolk, and State of Massachusetts, have invented a new and useful improvement in the Mode of Casting Type on the Periphery of Printing-Wheels or Disks, of which the following is a full, clear, and exact description, reference being had to the accompanying drawings, making a part of this specification, in which—

Figure 1 represents a plan view of the mould with the cover removed; and

Figure 2, a section of the same on the line xx of fig. 1.

The object of this invention is to provide a means for casting letters, figures, or other devices on the periphery of a circular disk or wheel, and is more especially designed to be applied to wheels used in cancelling or hand-stamps, and the invention consists of a circular mould-block provided with a series of radial recesses or grooves extending entirely around the same, in which are fitted a corresponding series of mould sections, the outer ends of which are on a line with the exterior rim of the mould-block, and their inner ends provided with suitable letters or figures facing an inner space in the mould-block; the whole being surrounded by a divided ring held in position by means of springs on either side.

Referring to the drawings, A represents the base-plate upon which is supported the mould-block B. The mould-block B consists of a solid circular piece of metal; with a circular recess in the centre, and having a series of radial recesses or grooves formed with square or parallel sides, and extending from the edge of the central circular recess to the exterior rim or edge of the mould-block. Within these recesses are fitted a corresponding series of mould sections C, being flush at their outer ends with the perimeter of the mould-block, and having sunk on their inner ends, any letters, figures, or other device that may be desired. Around the mould-block and sections is fitted a divided ring, D, which may be readily closed upon the said block and sections, so that the latter may be held in place, and as readily removed to allow the sections to be slipped out from the recesses, when the casting is completed. The said ring D is held in position around the block and sections by means of a spring, E, placed between it and a pin or projection, P, on the base. The whole is surmounted by a cover, F, provided with a suitable opening for the admission of the melted metal in the mould. The ring D that surrounds the mould sections is made in two parts in order to allow it to yield to the pressure occasioned by the expansion of the melted metal in the mould, as a solid or entire ring would be liable to break, and the springs, which may be of any suitable form or material, can be made rigid enough to retain the ring in place during the process of casting. The mould-block may be of any thickness required, so as to allow mould sections of any desired width vertically to be placed in the recesses of the same, and instead of a wheel, a cylinder may be formed in the mould, and in such a case the core may be enlarged so as to cast a cylinder with a rim of any required thickness to receive the impressions of the type on.

In operation the mould sections are slid into the recesses of the block, when the ring is placed around the same and held in position by the springs E. The cover is placed over the whole, and the metal poured into the mould. When sufficiently cool, the cover is taken off, the springs are removed, and the ring taken away, which allows the mould sections to be readily slid out from the recesses, leaving the finished wheel to be easily taken out.

Having thus described my invention, what I claim as new, and desire to secure by Letters Patent, is—

1. I claim the movable mould sections C, in combination with the mould block B, whereby impressions may be cast upon the perimeter of a circular disk or wheel, or the surface of a cylinder, substantially as set forth.
2. The mould-block B, provided with recesses for the reception of the mould sections, substantially as specified.
3. I claim confining the mould sections in place by means of a divided ring, in combination with a spring or springs, as and for the purpose specified.

In testimony whereof I have signed my name to this specification in the presence of two subscribing witnesses.

DEXTER H. CHAMBERLAIN.
